CONTROL SYSTEM

Harry S. Jones, Washington, D. C., assignor to
The Brown Instrument Company, Philadelphia,
Pa., a corporation of Pennsylvania

Application August 22, 1941, Serial No. 407,875

9 Claims. (Cl. 236—15)

The present invention relates to combustion control systems for fuel burners.

It is an object of the present invention to provide a combustion control system which operates in accordance with a characteristic of the fuel burner flame.

Another object of the invention is to provide a control system for controlling the quality or extent of combustion in a fuel burner which relies in its operation upon the electrical conductance of the fuel burner flame.

Another object of the invention is to provide a combined combustion quality and safety control system for a fuel burner which relies in its operation upon the conductance between a pair of spaced electrodes in engagement with the fuel burner flame and otherwise insulated from each other. Another and more specific object of the invention is to provide means for indicating quality of combustion in such a combined safety control system.

A further object of the invention is to provide a simplified safety control system for a fuel burner which employs a pair of electrodes in engagement with the burner flame and which is sensitive to the presence of a flame between the electrodes but is insensitive to other conductive paths therebetween.

Various arrangements independent of safety control provisions have been proposed in the prior art for determining the quality of combustion in a fuel burner, or more specifically, for determining the degree of combustion of the fuel in the burner and for controlling the mixture of fuel and air to the burner to secure optimum combustion conditions. In addition to the prior art, a copending application of Walter P. Wills, Serial No. 332,119, entitled Control apparatus, and filed April 27, 1940 issued into Patent 2,352,143 on June 20, 1944, discloses a combined combustion quality and safety control system for a fuel burner which relies in its operation upon the characteristic of a fuel burner flame of continuously fluctuating in resistance, and the further characteristic that the amplitude of the fluctuations varies inversely with the degree of combustion of the burning fuel.

The present application discloses a combined combustion quality and safety control system of the general type disclosed in the Wills patent referred to, but relies in its operation upon the characteristic of a fuel burner flame of being lower in resistance than the surrounding medium, namely the surrounding air, and upon the further characteristic of a fuel burner flame of varying in ohmic resistance in accordance with the

quality of combustion or degree of combustion of the fuel.

As is well known in the prior art all flames are the result of a chemical reaction. In the case of a gas flame, for example, the oxygen of the air combines with carbon and hydrogen of the fuel to form carbon dioxide and water vapor. The flame is always accompanied by ionized particles which are the result of the reaction between the oxygen of the air and the carbon and hydrogen of the gas. These particles or ions are capable of conducting a current between the burner and an electrode inserted in the flame.

With the burner as one electrode and a movable electrode inserted in the flame, it has been determined that the conductivity of a flame is greater in the direction opposite to that of the direction of flame propagation when the movable electrode is held in the outer parts of the flame and that when the movable electrode is moved toward the burner a region is reached where the flame conductivity becomes substantially equal in both directions of current flow between the burner and the movable electrode. This region is near the tip of the inner cone of the flame. By the term "direction of flame propagation" is meant the direction away from the burner. If the movable electrode is moved through this region toward the burner, another region is encountered where the conductivity of the flame is greater in the direction of flame propagation than in the other direction. This phenomena is believed to be due to the presence of a concentration of positive ions in the base of the flame. The negative ions or electrons of the ionized particles of the flame are much more mobile than the positive ions and tend to accumulate in the outer region of the flame while the positive ions tend to accumulate in the region closely adjacent the burner.

I have discovered that when the relation of the flame electrode and the burner is fixed, the ohmic resistance of a fuel burner flame varies inversely with the quality or extent of combustion of the fuel. Specifically, when the flame is yellow, containing a large quantity of unburned carbon, the ohmic resistance of the flame is greater than when the flame is blue, indicating more complete combustion of the fuel. As the quality of combustion of the fuel is varied to gradually change the flame from yellow to blue, the ohmic resistance of the flame varies gradually in a corresponding manner.

Advantage of these characteristics of a fuel burner flame is taken in the arrangement of my present invention, which arrangement relies in its operation on the ohmic resistance of a flame

to detect the presence of a flame, and is responsive to the magnitude of the ohmic resistance of the flame to provide a measure of the quality or degree of combustion of the burning fuel.

In safety control systems for fuel burners which have been proposed in the prior art, various means have been employed for determining if combustion conditions are proper and whether combustion actually takes place, one such means comprising an electrode which extends into the flame of the burner and which is so connected in the system as to provide a conductive path of relatively low resistance to ground through the flame. The variation in the electrical conductivity of this path to ground when the flame is present and when a flame is not present is commonly employed to change the bias on the control grid of an electronic valve for controlling a thermal safety switch. Since there is a possibility that a low resistance path may be set up from the electrode to ground through other agencies than by means of the flame, for example, a low resistance path which may be established between the electrode and ground by reason of carbonization, by accidental touching of the electrode to ground, or other abnormal conditions simulating combustion, provisions have been made in devices of the prior art for preventing the fuel supply and ignition from being turned on when such an abnormal condition exists.

Since an abnormal condition of this character simulating combustion may arise after the system is already in operation, it is desirable to provide means for distinguishing between such abnormal conditions and actual combustion while the system is in operation. For example, in a thermostatically controlled house heating system if the control system is insensitive to the presence of the flame after initial ignition of the flame, the fuel feeding means will be operated continuously as long as the room thermostat is closed. If the flame should then be extinguished, the furnace will be flooded with atomized fuel and a highly explosive mixture of the latter will be permitted to accumulate.

In accordance with the teachings of the prior art of which I am aware, when the flame electrode is maintained at a negative potential with respect to the potential of the burner, only a single electronic valve is required to control the operation of the burner in a safe manner responsive to the presence or absence of a flame at the burner. When the flame electrode is maintained at a positive potential with respect to the burner, however, at least two electronic valves are necessary. Two electronic valves are necessary in the latter because if only a single electronic valve is used, the output current of the valve will be a maximum when there is no flame at the burner and will be a minimum when there is a flame at the burner. The deenergized condition of the valve and the condition of the valve when there is a flame at the burner thus are the same. Such a condition is obviously not desirable in a safety control system, and accordingly, a second electronic valve is provided to effect a reversal in the output current obtained upon the appearance and disappearance of a flame at the burner, that is, to produce a maximum current when there is a flame at the burner, and a minimum current when there is no flame at the burner.

In respect to the number of electronic valves required in the safety control arrangement, therefore, the use of a negative flame electrode is to be preferred over a positive flame electrode. The negative flame electrode arrangement, how-

ever, is subject to a disadvantage to which the positive flame electrode arrangement is not subjected, namely, that the position of the flame in which the electrode must be positioned for proper operation is critical. This critical region is within the inner cone and close to the burner. If the flame electrode is moved away from this critical region in the flame, even though not entirely out of the flame, the system does not operate properly but operates just as if there was no flame.

It is accordingly another object of my present invention to provide a safety control system for a fuel burner in which a negative flame electrode may be utilized thereby permitting the use of a single electronic valve and in which the relation of the flame electrode and the burner is fixed, the flame electrode and the burner being provided in the form of a unitary and mechanically rigid assembly and in this manner obviating the possibility of displacement of the flame electrode from the critical region of the flame.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described a preferred embodiment of the invention.

Of the drawings.

Fig. 1 is a schematic diagram of an embodiment of a combined combustion quality and safety control system as applied to a fuel burner in which the flame electrode is negative in potential with respect to the burner potential;

Fig. 2 is an enlarged view in section of a portion of the arrangement of Fig. 1;

Fig. 3 is a schematic diagram of another embodiment of a combined combustion quality and safety control system as applied to a fuel burner in which the flame electrode is positive in potential with respect to the burner potential; and

Fig. 4 is an enlarged view in section of a portion of the arrangement of Fig. 3.

Fig. 1 of the drawings illustrates a gas burner supplied with gas through a conduit 2 and the flow of gas to the burner is controlled by an electrically operated or other suitable valve 3. A pilot burner 4 is provided which is controlled by an electrically operated or other suitable valve 5, and means are provided for igniting the pilot flame including a pair of electrodes 6 which are connected to the terminals of a secondary winding 7 of an ignition transformer 8 having a primary winding 9 which is adapted to be energized from the alternating current supply lines L¹ and L².

The fuel valve operating circuit of the control system illustrated in Fig. 1 is controlled by means of a thermostat 10 which may be located in a room or space to be heated. The thermostat 10 may be of any suitable construction and includes a bimetallic element 11 connected by means of a conductor 12 to the line L² and a contact blade 13 adapted to engage a stationary contact 14 which is connected to line L¹ through a thermal safety switch 15 and a secondary winding 16 of a transformer 17.

The thermal safety switch 15 is preferably of the form disclosed in Patent 1,958,081 to F. S. Denison, May 8, 1934. As shown more or less diagrammatically in the drawings, this switch 15 comprises a stationary arm 18 and a movable

arm 19 biased for movement away from arm 18 but normally held in engagement with the latter by means of a bimetallic element 20. Element 20 is rigidly secured at one end to a block 21 and is arranged to be heated by a coil 22 when the latter is energized through a circuit which will later be described. Upon energization of coil 22 for a predetermined period of time, element 20 will be warped sufficiently in the counter-clockwise direction to permit arm 19 acting under spring or other bias to separate from switch arm 18 thereby interrupting the circuit including the thermostat 10. The switch 15 will remain locked in this position until manually returned to its normally closed position.

Both the main burner 1 and the pilot burner 4 are supplied with a combustible mixture of fuel and air from a mixing chamber 23 into which fuel is introduced through a conduit 24 and air through the conduit 25. As shown, a fuel pressure regulator 24A is inserted in the fuel supply conduit 24. The amount of air passing through the conduit 25 is controlled by an electrically operated or other suitable valve 26 which is adapted to be energized from the alternating current supply lines L₁ and L₂.

The transformer 17 which supplies power for the control system is a combination step-up, step-down transformer and comprises the primary winding 16, low voltage secondary windings 27, 28 and 29, and a high voltage secondary winding 30. The low voltage secondary winding 27 is connected by conductors 31 and 32 to the heater filaments 33 and 34 of an electronic valve 35 and supplies energizing current thereto. The electronic valve 35 is a twin type amplifier valve and includes two triodes, designated A and B, in one envelope. For convenience the triode designated A in the drawings will be referred to hereinbefore as the rectifier and the triode B will be referred to as the detector. The rectifier A includes the heater filament 33, a cathode 36, a control electrode 37 and an anode 38, and the detector B includes the heater filament 34, a cathode 39, a control grid 40, and an anode 41.

The rectifier A is supplied with electrical energy from the upper portion of the transformer secondary winding 30 through a circuit which may be traced from the upper terminal of winding 30 to a conductor 42, anode 38, cathode 36, and a conductor 43, in which a resistor 44 is inserted, to the tap 45 intermediate the ends of winding 30. This circuit is conductive only during the half cycles of the alternating voltage supply source when the upper terminal of winding 30 is positive with respect to the lower terminal thereof due to the action of the rectifier A. Thus, a pulsating potential drop is produced across resistor 44 in the direction to render terminal 46 of resistor 44 positive with respect to terminal 47 thereof. The control electrode 37 of rectifier A is directly connected to the cathode 36.

The output circuit detector B is supplied with electrical energy from the lower portion to the transformer secondary winding 30 through a circuit which may be traced from the lower terminal of winding 30 through a conductor 48, winding 49 of a relay 50 in shunt with a condenser 51, winding 52 of a relay 53 in shunt with a condenser 54, an electric meter 55, anode 41 of detector B, cathode 39 and a conductor 56, switch arm 62, contact 61 and conductor 60 to the tap 45 on winding 30.

It will thus be noted that the output circuit 75

of the detector B includes the relay windings 49 and 52 and the electric meter 55 in series and that this output circuit is energized by the portion of the transformer secondary winding 30 which is below the tap 45.

The current flow in the output circuit of detector B is controlled by an input circuit one branch of which connects the control electrode 40 to the cathode 39 through a connection including a pair of resistors 57 and 58 in series and shunted by a condenser 59, conductor 60, contact 61, a switch arm 62 and conductor 56. During the normal operation of the system the switch arm 62 is held away from the contact 61 but is in engagement with the latter at certain times for a purpose later described.

A second branch of the input circuit of the detector B connects the control electrode 40 through a conductor 63 to an electrode 65 which projects into the flame of the pilot burner 4. The conductor 63 is preferably encased within a shield 63A which, as shown is connected to the lower terminal of resistor 58. The pilot burner 4 is connected to ground and thereby to the positive terminal of resistor 44, which terminal as shown is also grounded. In this arrangement, therefore, the flame electrode 65 is maintained at a negative potential with respect to the potential of the burner 4. As illustrated in Fig. 1 and in more detail in Fig. 2, the burner 4 and flame electrode 65 are provided in the form of a unitary mechanical assembly, the flame electrode being insulated from the burner 4 by an electrical insulator 65A. The insulator 65A is preferably of a type capable of withstanding the high temperatures encountered near the burner 4. The flame electrode 65 in this arrangement is positioned close to the burner 4 and is preferably so positioned as to always be within the region of the inner cone irrespective of the quality of combustion of the burning fuel.

A third branch of the input circuit of detector B connects the control electrode 40 to the cathode 39 through a connection including the resistors 57 and 58 shunted by condenser 59, a conductor 64, the transformer secondary winding 28, a contact 65, switch arm 62, and conductor 56 to the cathode 39.

During the normal operation of the system 50 the resistor 58 is shunted by a connection which may be traced from the upper end of resistor 58 through a conductor 66, a switch arm 67, a contact 68, and a conductor 69 to the lower terminal of resistor 58. The reason for providing 55 the resistor 58 is explained hereinafter.

The transformer secondary winding 30 is so wound on transformer 17 that the detector B is conductive only on the half cycles when the rectifier A is not conductive and vice versa. Thus, a pulsating direct current potential drop is produced across resistor 44 during the half cycles when the detector B is non-conductive. The phase of this pulsating potential drop is such that it will be at a maximum value when the anode 41 of detector B is negative. This pulsating potential drop produced across resistor 44 is applied to the input circuit of the detector B through the flame if present, and the polarity thereof is such as to cause a pulsating direct current to flow through the flame in the direction of flame propagation. The circuit through which this pulsating current flows has been described hereinbefore.

When the burner operation is first initiated and a flame is not present at the burner and no

other conductive path exists from the control electrode 40 to ground, no biasing potential will be applied to the control electrode 40 of detector B. The control electrode 40 of detector B will be at substantially the same potential as the cathode 39 since the control electrode 40 and cathode 39 are then connected by resistors 57 and 58, conductor 60, contact 61 and switch arm 62 then in engagement and conductor 56. As a result the detector B will be conductive during 10 the time its anode 41 is positive.

In the normal operation of the system, when a flame is present at the burner, the switch arm 62 is actuated away from contact 61 and into engagement with the contact 65 to thereby connect the transformer secondary winding 28 in the input circuit of the detector B. The transformer secondary winding 28 is so wound on the transformer 17 that it tends to apply a negative potential to the control electrode 40 of detector B and thereby tends to reduce the current flow in the output circuit of the latter.

Upon the appearance of a normal flame, the bias potential produced across resistor 44 is applied to the control electrode 40 of detector B through the resistance of the flame. The resulting flow of current through the resistance of the flame produces a potential across resistors 57 and 58 which is stored on the condenser 59 and is of the proper polarity to tend to apply a positive potential to the control electrode 40, and thereby to oppose the tendency of transformer secondary winding 28 to apply a negative potential to the control electrode 40. This potential is stored on the condenser 59 during the half cycles when the rectifier A is conductive and the detector B is non-conductive, and is maintained on the condenser 59 during the succeeding half cycles when the anode 41 of detector B is positive. This result is accomplished by properly proportioning condenser 59 and resistors 57 and 58. It is therefore seen that appreciable current flows in the output circuit of the detector B during the condition of normal flame.

If the flame electrode is grounded, that is, if a path more conductive than a flame exists between the flame electrode and ground, the charge which is stored on the condenser 59 during the half cycles when the anode 41 of detector B is negative will leak off through that conductive path during the same half cycle and the initial portion of the succeeding half cycle to thereby substantially reduce the potential on the condenser 59 during said succeeding half cycle. Consequently, the potential applied to the control electrode 40 is rendered more negative due to the action of transformer secondary winding 28 and as a result the current flow in the output circuit of detector B will be decreased.

It will thus be noted that current flows in the output circuit of detector B when there is a flame at the burner and that little or no current flows in this output circuit when there is no flame and when the flame electrode 65 is grounded.

As illustrated in Fig. 1, the relay 50 comprises the winding 49 and switch arms 70 and 71 which are controlled by the winding 49 and which cooperate with front contacts 72 and 73, respectively. Switch arms 70 and 71 also cooperate with back contacts 74 and 75, respectively, and are biased downward by gravity or spring means, not shown, into engagement with the latter contacts. For convenience, a contact through which a circuit is completed when a relay is energized

5 will be designated a front contact of the relay, and a contact through which a circuit is completed when the relay is deenergized will be designated a back contact.

There are also provided two relays 16 and 17 which are utilized for purposes explained hereinafter. Relay 16 comprises a winding 78 which operates a switch arm 79 in addition to the switch arm 62 previously mentioned. The switch arm 79 cooperates with a front contact 80. Relay 17 comprises a winding 81 which operates switch arms 82 and 83 in addition to the switch arm 67 previously mentioned. The switch arms 82 and 83 cooperate with front contacts 84 and 85 respectively. The switch arms 62 and 79 of relay 16 and switch arms 61, 82 and 83 of relay 17 are biased downward by gravity or spring means, not shown.

When the temperature of the room or space to be heated is higher than the desired value all parts of the system are in the positions shown in Fig. 1 and the fuel burner is then deenergized. If the temperature of the room or space to be controlled falls below the value it is desired to maintain, the thermostat 10 operates to move the switch blade 13 into engagement with the contact 14. This results in closure of an energizing circuit to the transformer primary winding 16 and thereby effects energization of the transformer secondary windings. At this time the switch arm 62 is in engagement with the contact 61 and as a result the detector B is immediately rendered conductive as soon as the cathode 39 20 has been heated sufficiently and effects energization of the relay winding 49. The relay 50 25 then operates switch arm 70 into engagement with front contact 72 to complete an energizing circuit for the winding 78 of relay 16 in series with the heater coil 22 of the thermal safety 30 switch 15. This circuit may be traced from the upper terminal of a secondary winding 29 through a conductor 86, winding 78, a conductor 87, heater coil 22, a conductor 88, switch arm 70, 35 contact 72, and a conductor 89 to the lower terminal of the winding 29.

The energization of the winding 78 causes the switch arm 79 to close on the front contact 80 to complete a holding circuit for the winding 78. This holding circuit may be traced from the upper terminal of winding 29 through conductor 86, winding 78, switch arm 79 and contact 80 to the lower terminal of winding 29. Winding 78 of relay 16, when energized, also actuates switch arm 62 out of engagement with the contact 61 40 and into engagement with contact 65' thus connecting the transformer secondary winding 28 into the input circuit of the detector B. As noted above the transformer secondary winding 28 tends to apply a negative potential to the control electrode 40 of the detector B. It is noted that the condenser 51 connected in shunt to relay winding 49 is so proportioned as to introduce a time delay in the operation of relay 50 as required to prevent the momentary opening of the 45 output circuit of detector B caused by actuation of switch arm 62 from contact 61 to contact 65' from resulting in deenergization of the relay 50.

Before the starting cycle is allowed to proceed further, however, a check is made to detect 50 the presence of leakage resistance paths between the electrode 65 and ground and initiation of the burner flame is prevented in a manner described hereinafter if such leakage paths exist and are of the order of a normal flame resistance or 55 slightly higher as desired. This desirable fea-

ture is obtained by an interlocking of the relays 50 and 76 to the end that the cycle cannot proceed further until the relay 50 has been deenergized and then reenergized. If the resistance of the path between the flame electrode 65 and ground is of the order of a normal flame, a charge is stored on the condenser 59 which maintains the detector B conductive where the relay 50 is not deenergized.

The resistor 58 which is connected in series with the resistor 57 is provided to accomplish this result. At this point in the starting cycle of the system the shunt circuit for the resistor 58 is open at the switch arm 67. The resistor 58, therefore, is now effectively connected in the input circuit of the detector B and operates to place a higher resistance in shunt to the condenser 59, and as a consequence, a higher average positive potential is maintained on the control electrode 40 by the condenser 59 than would be maintained therein if the resistance 58 were shunted out. The detector B at this point in the starting cycle of the system is therefore sensitive to conductive paths between the electrode 65 and ground of resistance greater than that of a normal flame. If such conductive paths exist the detector B will remain conductive and the system will continue in the condition last described, namely, with the relays 50 and 76 energized. The magnitude of the resistance of such leakage paths from electrode 65 to ground to which the detector B is sensitive is determined by the capacitance of condenser 59 and the total value of resistors 57 and 58.

If no such leakage conductive paths exist between the flame electrode 65 and ground, however, no potential is stored on the condenser 59, and accordingly, detector B becomes non-conductive and the relay 50 is deenergized. This causes switch arm 70 to close back contact 74 to thereby complete an energizing circuit for the winding 81 of relay 77. This energizing circuit may be traced from the upper terminal of transformer secondary winding 29 to conductor 86, winding 81, a conductor 90, contact 74, switch arm 70, conductor 88, heater 22, conductor 87, switch arm 79 and contact 80 to the lower terminal of winding 29.

Energization of the relay 77 causes it to close a holding circuit for itself, causes it to shunt the resistor 58, and causes it to energize the ignition transformer primary winding 9 and the pilot fuel valve 5. The holding circuit for relay 77 may be traced from the upper terminal of winding 29, conductor 86, winding 81, switch arm 82, contact 84, conductor 88, heater 22, conductor 87, switch arm 79, and contact 80 back to winding 29. The resistor 58 is shunted by the closure of switch arm 67 on the front contact 68 through the conductors 66 and 69. The energizing circuit for the ignition transformer circuit 9 may be traced from the alternating supply line L¹ through a conductor 91, the primary winding 9, back contact 75, switch arm 71, contact 85, switch arm 83, and a conductor 92 to the supply line L². The energizing circuit for the pilot fuel valve 5 may be traced from the supply line L¹ through conductor 91, a conductor 93, pilot fuel valve 5, a conductor 94, front contact 85, switch arm 83, and conductor 92 to the supply line L².

As a result of the energization of the ignition transformer 8 and the pilot fuel valve 5 a flame should appear at the pilot burner 4. If no flame appears, no further action will take place until the system is deenergized by the action of the

heater coil 22 and the thermal safety switch 15. If a flame appears, however, detector B will become conductive as previously described, and consequently relay 50 will again be energized.

Reenergization of relay 50 causes the closure of a short circuit around the heater coil 22, opening of the energizing circuit through the ignition transformer primary winding 9, and energization of the main fuel valve 3. The burner 4 is then in full operation. The short circuit around the heater coil 22 may be traced from the left end thereof as seen in Fig. 1 to conductor 88, switch arm 70, front contact 72, conductor 89, front contact 80, switch arm 79, and conductor 87 to the other end of heater coil 22. The energizing circuit of transformer primary winding 9 is opened by the movement of switch arm 71 away from the back contact 15. The energizing circuit to the main fuel valve 3 may be traced from the supply line L¹ through conductor 91, a conductor 94, pilot fuel 3, a conductor 95, front contact 73, switch arm 71, front contact 85, switch arm 83, and conductor 92 to the supply line L².

If after the burner has been placed in full operation the flame should become extinguished or if the flame electrode 65 should be grounded, the detector B will become non-conductive and relay 50 will be deenergized, thus causing the main burner valve 3 to close, effecting reenergization of the ignition transformer 8 and causing opening of the shunt circuit around the heater coil 22 of the thermal safety switch 15. If the flame then reappears the burner will go again into full operation. If the flame does not reappear within a predetermined time, however, the system will be deenergized by the opening of the thermal safety switch 15 due to the action of the heater coil 22.

From the foregoing it will be seen that the system of Fig. 1 is adapted to distinguish between normal flame conditions and abnormal conditions at the burner 4 and operates to deenergize the system if an abnormal condition prevails longer than a predetermined time.

The relay 53 comprises the winding 52 and a switch arm 96 which is adapted to cooperate with a front contact 97 and a back contact 98. The switch arm 96 is biased downward by gravity or spring means to close on its back contact 98 and is adapted to be moved against that bias and against the opposing force of a compression spring 99 into engagement with the front contact 97. If the current flow through the relay winding 52 gradually increases from zero, it first overcomes the opposing downward bias on the switch arm 96 and lifts arm 96 upward until it engages spring 99. The spring 99 then balances the attraction of the relay winding, and holds the switch arm 96 separated from both its front and back contacts. If the current flow through winding 52 continues to increase it eventually becomes sufficient to overcome the opposing effect of the action of gravity on the switch arm 96 and the opposing effect of spring 99 to close switch arm 96 on its front contact 97. By adjusting the force biasing the switch arm 96 downwardly and the compression of spring 99, the current levels at which these two actions of relay 53 take place may be adjusted as desired.

The air controlling valve 26 is operated by a reversible electrical motor (not shown) which is energized for rotation in one direction through a circuit which may be traced from the supply line L¹ through conductors 91 and 94 to the valve 26, a conductor 100, back contact 98, switch

arm 96, a conductor 101, and conductor 92 to the supply line L², and is energized for rotation in the opposite direction through a circuit which may be traced from the supply line L¹ through conductors 91 and 94 to the valve 26, a conductor 102, front contact 97, switch arm 96, and conductors 101 and 92 to the supply line L². The motor is adapted to open the valve when it is energized through contact 98 and conductor 100 and to close the valve when energized through front contact 97 and conductor 102. The valve 26 is provided with a limit switch (not shown) which operates to open conductor 100 and thereby to deenergize the motor when the valve has been adjusted to its fully opened position. A second limit switch (not shown) is also provided for opening the conductor 102 and thereby deenergizing the motor when the valve 26 has been closed. The limit switch is preferably so adjusted that the valve can never be completely closed.

When the system operation is first initiated the switch arm 96 will be in the position shown, the valve 26 will be in its open position and the fuel mixture will accordingly be lean. This will result in the establishment of a blue flame presenting relatively low resistance to the flow of current therethrough and as a result the effective current flow in the output circuit of the detector B and through relay winding 52 will be sufficient to close the switch arm 96 against contact 97. This will energize the motor of valve 26 in the direction to close the valve. As the valve 26 closes less air is supplied to the mixing chamber 23. Such adjustment of the valve is made until the desired mixture of fuel and air and consequently the desired quality of combustion is obtained. Specifically, as the supply of air to the mixing chamber is thus decreased, the resistance of the flame increases and the current through the relay winding 52 decreases until it reaches a value at which the switch arm 96 is biased by the action of gravity and the spring 99 out of engagement with the contact 97 and is also held out of engagement with contact 98. The fuel mixture will then have its proper proportions and the valve setting will remain constant until a change in fuel combustion quality caused by a change in fuel B. t. u. content, for example, causes a change in the resistance between the flame electrode 65 and ground. Upon a change in resistance of the flame between the flame electrode 65 and ground, the current flow in the output circuit of detector B is changed in the proper direction to effect actuation of the valve 26 in the proper direction to restore the quality of combustion of the fuel to the desired value. As will be apparent to those skilled in the art the meter 55 through which the output current of detector B flows may be calibrated in terms of fuel combustion quality to thereby provide a direct indication of the quality of combustion of the fuel.

It will be clear from the foregoing explanation that the combustion control system illustrated in Fig. 1 controls a fuel burner in accordance with the presence or absence of a flame, and in addition to controlling the proportions of a fuel mixture so as to obtain efficient combustion, also provides an indication of the quality of combustion of the fuel. Moreover, as will be apparent to those skilled in the art, either of these functions may be obtained without the other.

In Fig. 3 I have illustrated, more or less diagrammatically, a modification of the combined combustion quality and safety control system

shown in Fig. 1 wherein a positive potential is impressed on the flame electrode relatively to the potential of the burner. In this modified arrangement, as shown in Fig. 3 and in more detail in Fig. 4, the flame electrode which has been designated by the reference character 65 B is positioned further away from the burner 4 than in the arrangement of Fig. 1 and preferably is at such a distance from the burner 4 as to never come in contact with the inner cone over the whole range of combustion quality variation of the flame. The burner 4 and the flame electrode 65B in this arrangement, as in the arrangement of Fig. 1, are desirably provided in the form of a unitary mechanical assembly and are insulated from each other by means of the insulator 65A. In Fig. 3 elements corresponding to those in the Fig. 1 arrangement have been designated by the same reference numerals.

same reference numerals.

20 In Fig. 3 electric power is supplied to the system from a combination step-up and step-down transformer 103 which comprises a line voltage primary winding 104 and high voltage secondary windings 105, 106 and 107 and low voltage secondary windings 108, 109 and 28. The low voltage secondary winding 108 is connected by conductors 110 and 111 to the filament type cathode 112 of an electronic tube 113 and supplies energizing current thereto. The electronic tube 30 113 is a diode-triode-power amplifying pentode, for example, a type 1D8GT and includes a diode designated by the reference character C, a triode designated by the reference character D, and a pentode designated by the reference character 35 E. The diode or rectifier C includes the filament cathode 112 and an anode 114, the triode D includes the filament cathode 112, a control electrode 115 and an anode 116, and the power amplifier pentode E includes the filament cathode 40 112, a control electrode 115 and an anode 116, and the power amplifier pentode E includes the filament cathode 112, a control electrode 117, a screen electrode 118, a suppressor electrode 119, and an anode 120. As shown the cathode 112 and the suppressor electrode 119 are directly 45 connected to each other within the tube 113.

The rectifier C is supplied with electrical energy from the transformer secondary winding 106 through a circuit which may be traced from the upper terminal of winding 106 through a conductor 121, anode 114, filament cathode 112 and a conductor 122 in which a resistor 123 is inserted to the lower terminal of winding 106. This circuit is conductive only during the half cycles of the alternating voltage supply source when the upper terminal of winding 106 is positive with respect to the lower terminal thereof due to the action of rectifier C. Thus, a potential drop is produced across resistor 123 in the direction to render terminal 124 positive with respect to terminal 125.

The triode D in the arrangement of Fig. 3 is utilized as a detector and is supplied with electrical energy from the transformer secondary 65 winding 105 through an output circuit which may be traced from the lower terminal of the winding 105 through a conductor 126, anode 116, filament 112, a conductor 127, winding 109, a conductor 128 in which a resistance 129 is inserted and a conductor 130 to the upper terminal of winding 70 105.

The conductivity of the output circuit of detector D is controlled by an input circuit one branch of which connects the control electrode 75 115 to the grounded negative terminal 125 of the

resistor 123 through a connection including a resistor 131, a conductor 132, the switch arm 62 of relay 76, and contact 61 which is grounded. In this arrangement the contact 65' of relay 76 has been dispensed with. During the normal operation of the system, the switch arm 62 is held away from the contact 61 but is in engagement with the latter during the time of initiation of operation of the system in order to effect the initial energization of relay 50, and is moved out of engagement with the contact 61 to effect de-energization of relay 50 if the proper conditions for operation exist between the flame electrode and ground.

A second branch of the input circuit of the detector D connects the control electrode 115 through conductor 63 to the electrode 65B which projects into the flame of the pilot burner 4. The pilot burner 4 is connected to ground. As shown, the conductor 63 may desirably be provided with a shield 63A.

A third branch of the input circuit of detector D connects the control electrode 116 to the filament cathode 112 through a parallel connection including resistors 131 and 133 in one arm and a condenser 134 in the other arm. The resistor 133 corresponds to the resistor 58 of the Fig. 1 arrangement and is normally shunted by a connection which may be traced from the upper terminal of resistor 133 to conductor 132, switch arm 67, contact 68 and conductor 69 to the lower terminal of resistor 133. The resistor 133 in this arrangement is provided for the same purpose for which the resistor 58 of the Fig. 1 arrangement is provided, namely, for the purpose of detecting the presence of high resistance leakage paths between the flame electrode 65B and ground.

The transformer secondary windings 106 and 105 are so wound on transformer 103 that the detector D is conductive only on the half cycles when the rectifier C is non-conductive and vice versa. Thus, a pulsating potential drop is produced across resistor 123 during the half cycles when the detector D is non-conductive. The phase of this pulsating potential drop is such that it will be at a maximum value when the anode 116 of detector D is negative, and zero when the anode 116 of detector D is positive.

The pulsating potential drop or biasing potential produced across the resistor 123 is applied to the input circuit of the detector D through the flame, if present, and the polarity thereof is such as to cause a pulsating direct current to flow through the flame in the direction opposite to the direction of flame propagation. This input circuit may be traced from the positive terminal 124 of resistor 123, conductor 122, resistors 133 and 131 shunted by condenser 134, conductor 63, flame electrode 65B, burner 4 to ground, and through ground to the negative terminal 125 of resistor 123.

When a flame is not present at the burner and the switch arm 62 and contact 61 are out of engagement and no other conductive path exists from the control electrode 115 to ground, no bias potential will be applied to the control electrode 115 and the latter will then be at substantially the same potential as the cathode 112 since the control electrode 115 and cathode 112 are directly connected by resistors 131 and 133. As a result, the detector D will then be conductive during the time the anode 116 is positive.

Upon the appearance of a normal flame the bias potential produced across resistor 123 is ap-

plied to the control electrode 115 through the resistance of the flame. The resulting flow of current through the resistance of the flame produces a potential across resistor 131 which is stored on the condenser 134 and is of the proper polarity to apply a negative potential to the control electrode 115 and thereby to reduce the current flow in the output circuit of the detector D. This potential is stored on the condenser 134 during the half cycles when the rectifier C is conductive and the detector D is non-conductive, and is maintained on the condenser 134 during the half cycles when the anode 116 is positive. This result is obtained by properly proportioning condenser 134 and resistor 131. The result is that little or no current is conducted in the output circuit of the detector D during the condition of normal flame.

If a path more conductive than a flame exists between the flame electrode and ground, the charge which is stored on the condenser 134 during the half cycles when the anode 116 is negative will leak off through that conductive path during the same half cycles and the initial portion of the succeeding half cycles to thereby substantially reduce the potential on the condenser 134 during the same half cycle. Consequently, the potential applied to the control electrode 115 is rendered substantially less negative and as a result current will flow in the output circuit of the detector D.

It will thus be noted that current flows in the output circuit of the detector D when there is no flame and when the flame electrode 65B is grounded, and that little or no current flows in this output circuit when the normal flame is present at the burner.

The current conducted by the detector D controls the potential difference between the terminals of the resistor 129, which potential difference in turn is utilized to control the conductivity of the pentode power amplifier E. The output circuit of amplifier E is supplied with energy from the transformer secondary winding 107 through an output circuit which may be traced from the lower terminal of winding 107 through a conductor 135, winding 49 of relay 50 which is shunted by condenser 51, winding 52 of relay 53 which is shunted by condenser 54, meter 55, anode 120 of amplifier E, cathode 112, and a conductor 136 to the upper terminal of winding 107. As shown, the screen electrode 118 of amplifier E is connected by conductors 137 and 135 to the lower terminal of winding 107.

The conductivity of the amplifier E is adapted to be controlled in accordance with the potential drop across resistor 129 and thereby in accordance with the condition of the path between the flame electrode 65B and ground. To this end the upper terminal of the resistor 129 is connected by a conductor 138 to the control electrode 117 of amplifier E, and the lower terminal is connected by conductor 128 and the transformer secondary winding 109 to the filament 112. These connections including the resistance 129 are hereinafter termed the input circuit of the amplifier E and are made in such a manner that when current flows in the resistor 129 from the detector D, the amplifier control electrode 117 is biased negatively with respect to the cathode 112 by an amount determined by a difference in potential between the terminals of the resistor 129 and the potential impressed on the input circuit by the transformer secondary

winding 109. The transformer secondary winding 109 tends to apply a positive potential to the control electrode 117 relatively to the potential of the cathode 112 while the potential drop produced across the resistor 129 by the output current from detector D tends to apply a negative potential to said control electrode.

Therefore, when the detector D is conductive, the amplifier E will become non-conductive. Conversely when detector D is non-conductive, no potential difference will exist across the resistor 129 and the amplifier E will become conductive.

From the foregoing it will be seen that the arrangement of Fig. 3 is adapted to distinguish between normal flame conditions and abnormal conditions at the burner and operates to de-energize the system for an abnormal condition prevailing longer than a predetermined time. The further operation of the arrangement of Fig. 3 upon a call for heat by the thermostat 10 and upon the appearance or disappearance of a flame at the burner 4 or upon the occurrence of an abnormal condition at the burner is substantially the same as that of the arrangement of Fig. 1 as described hereinbefore, and therefore, further description of the safety control provisions of the arrangement of Fig. 3 is believed unnecessary.

With respect to the operation of the combustion quality controlling provisions of the arrangement of Fig. 3, it is noted that when the system operation is first initiated the switch arm 96 will be in the position shown, the valve 26 will be in its open position and the fuel mixture accordingly will be lean, as in the arrangement of Fig. 1. This will result in the establishment of a blue flame at the burner which presents relatively low resistance to the flow of current through the flame, and accordingly, the effective current flow in the output circuit of the amplifier E and thereby to the relay winding 52 will be sufficient to close the switch arm 96 against the contact 97. This will effect energization of the motor valve in the proper direction to close the valve and thereby to reduce the supply of air to the mixing chamber 23. As the supply of air to the mixing chamber 23 is thus decreased, the fuel mixture is enriched, and as a result, resistance of the flame is increased and the current flow through the relay winding 52 decreases until it reaches a value at which the switch arm 96 is biased by the action of gravity and the spring 99 out of engagement with the contact 97, but is still held out of engagement with contact 98. The fuel mixture will then have its proper proportions and the valve setting will remain constant until a change in fuel combustion quality produced by a change in fuel B. t. u. content for example, causes a change in the flame resistance. Upon a change in resistance of the flame, the current flow in the output circuit of the amplifier E is changed by a corresponding amount and in the proper direction to effect actuation of the valve 26 in the proper direction to restore the quality of combustion of the fuel to the desired value.

It will be apparent from the foregoing explanation that the combustion control system described in Fig. 3 controls a fuel burner in accordance with the presence or absence of a flame at the burner and controls the proportions of a fuel mixture so as to obtain efficient combustion. These functions, if desired, may be obtained separately. A meter 55 calibrated in terms

of fuel combustion quality may also desirably be provided in this arrangement, as in the arrangement of Fig. 1, to provide a visual indication of the quality of combustion of the burning fuel.

Subject matter disclosed in this application but not claimed herein is disclosed and is being claimed in my copending application, Serial Number 404,523, filed July 29, 1941.

While, in accordance with the provisions of the statutes, I have illustrated and described preferred embodiments of the present invention, those skilled in the art will understand that changes may be made in the form of the apparatus disclosed without departing from the spirit of my invention as set forth in the appended claims, and that some features of the present invention may sometimes be used with advantage, without a corresponding use of other features.

Having now described my invention, what I claim as new and desire to secure by Letters Patent is:

1. A combined safety and quality control system for a fuel burner provided with fuel and air supply means and igniting means to establish a flame at said burner, a device to control the supply of fuel and air to said burner, a valve to control the mixture of fuel and air supplied to the burner, and a device to operate said valve, comprising in combination an electrode insulated from the burner and arranged to be connected to the burner by the flame and so positioned relatively to the burner as to contact the inner cone of the flame, a current responsive device to operate said first mentioned device, a current responsive device to operate said second mentioned device and having an operating characteristic such that when energized with current of a predetermined range it actuates said second mentioned device to open said valve and when energized with current of a different predetermined range it actuates said second mentioned means to close said valve, and means connected to said electrode and to the burner and including an energizing circuit adapted to be connected to a source of electrical energy to control the energization of said current responsive devices in accordance with the magnitude of the ohmic resistance of the path between said electrode and the burner and arranged to effect operation of said first mentioned device in the sense to prevent the supply of fuel to the burner when no flame is present at the burner and to effect operation of said second mentioned device in the sense to restore a desired quality of combustion of the flame upon variation in said quality of combustion, said last mentioned means including means to apply a potential on said electrode which is negative relative to the potential of the burner.

2. The combination of claim 1 wherein said electrode is mounted on the burner in such manner that the electrode and burner comprise a unitary mechanical assembly whereby the relation of said electrode and burner is fixed.

3. A combined safety and quality control system for a fuel burner provided with fuel and air supply means and igniting means to establish a flame at said burner, a device to control the supply of fuel and air to said burner, a valve to control the mixture of fuel and air supplied to the burner, and a device to operate said valve, comprising in combination an electrode insulated from the burner and arranged to be connected to the burner by the flame and so positioned

relatively to the burner as to contact the outer cone of the flame, a current responsive device to operate said first mentioned device, a current responsive device to operate said second mentioned device and having an operating characteristic such that when energized with current of a predetermined range it actuates said second mentioned device to open said valve and when energized with current of a different predetermined range it actuates said second mentioned means to close said valve, and means connected to said electrode and to the burner and including an energizing circuit adapted to be connected to a source of electrical energy to control the energization of said current responsive devices in accordance with the magnitude of the ohmic resistance of the path between said electrode and the burner.

4. The combination of claim 3 wherein said electrode is mounted on the burner in such manner that the electrode and burner comprise a unitary mechanical assembly whereby the relation of said electrode and burner is fixed.

5. A combined safety and quality control system for a fuel burner provided with fuel and air supply means and igniting means to establish a flame at said burner, a device to control said means having two operating conditions one permitting and the second preventing the establishment of a flame at the burner, and means to control the mixture of fuel and air supplied to the burner, comprising in combination an electrode insulated from the burner and positioned in the path of the flame and arranged to be connected to the burner by the flame, a current responsive device to operate said control device and adapted when energized to actuate said control device to its first mentioned operating condition and adapted when deenergized to actuate said control device to its second mentioned operating condition, a current responsive device to operate said mixture control means, and means connected to said electrode and to the burner and including an energizing circuit adapted to be connected to a source of electrical energy to control said current responsive devices in accordance with the magnitude of the ohmic resistance of the path between said electrode and the burner.

6. A combined safety and quality control system for a fuel burner provided with fuel and air supply means and igniting means to establish a flame at the burner, a device to control said fuel supply means, a valve to control the mixture of fuel and air supplied to said burner, and a device to operate said valve, comprising in combination an electrode insulated from the burner and positioned in the path of the flame and arranged to be connected to the burner by the flame, a current responsive device to operate said first mentioned device, a current responsive device to operate said second mentioned device and having an operating characteristic such that when energized with a current of a predetermined range it actuates said second men-

tioned device to open said valve and when energized with current of a different predetermined range it actuates said second mentioned device to close said valve, and means connected to said electrode and to the burner and including an energizing circuit adapted to be connected to a source of electrical energy to control the energization of said current responsive devices in accordance with the magnitude of the ohmic resistance of the conductive path between said electrode and the burner.

7. A combined safety and quality control system for a fuel burner provided with fuel and air supply means and igniting means to establish a flame at said burner, and a device to control said fuel supply means, and means to control the mixture of fuel and air supplied to the burner, comprising in combination an electrode insulated from the burner and positioned in the path of the flame and arranged to be connected to the burner by the flame, a device to operate said mixture control means, and means connected to said electrode and to the burner and including an energizing circuit adapted to be connected to a source of electrical energy to control said operating devices in accordance with the magnitude of the ohmic resistance of the conductive path between said electrode and the burner.

8. A combined safety and quality control system for a fuel burner provided with fuel and air supply means and igniting means to establish a flame at the burner, a device to control said fuel supply means, and means to control the mixture of fuel and air supplied to the burner, comprising an electrode insulated from the burner and positioned in the path of the flame and arranged to be connected to the burner by the flame, and means connected to said electrode and the burner and adapted to be connected to a source of electrical energy to control said control device and said mixture control means in accordance with the magnitude of the ohmic resistance of the path between said electrode and the burner.

9. A combined safety and quality control system for use with a fuel burner provided with fuel and air supply means and igniting means to establish a flame at said burner, a device to control said means having two operating conditions one permitting and the second preventing establishment of a flame at the burner, and means to control the mixture of fuel and air supplied to the burner, comprising in combination an electrode arranged to be connected to the burner by the flame, said electrode being mounted on the burner in such manner that said electrode and burner comprise a unitary mechanical assembly whereby the relation of said electrode and said burner is fixed, a current responsive device to operate said control device and adapted when energized to actuate said control device to its first mentioned operating condition and adapted when deenergized to actuate said control device to its second mentioned operating condition, a current responsive device to operate said mixture control means, and means connected to said electrode and to said burner and including an energizing circuit adapted to be connected to a source of electrical energy to control said current responsive devices in accordance with the magnitude of the ohmic resistance of the path between the electrode and burner.

CERTIFICATE OF CORRECTION.

Patent No. 2,361,294.

October 24, 1944.

HARRY S. JONES.

It is hereby certified that error appears in the printed specification of the above numbered patent requiring correction as follows: Page 1, first column, line 14, for "it is" read --in its--; page 3, first column, line 26, for "L₁ and L₂" read --L¹ and L²--; page 5, first column, line 8, for the word "where" read --whereby--; and that the said Letters Patent should be read with this correction therein that the same may conform to the record of the case in the Patent Office.

Signed and sealed this 15th day of May, A. D. 1945.

Leslie Frazer

Acting Commissioner of Patents.
